UNITED STATES PATENT OFFICE.

SAMUEL L. GRISWOLD KNOX, OF SAN FRANCISCO, CALIFORNIA.

TORPEDO PROTECTION.

1,243,427.

Specification of Letters Patent. Patented Oct. 16, 1917.

Application filed December 8, 1916. Serial No. 135,749.

To all whom it may concern:

Be it known that I, SAMUEL L. GRISWOLD KNOX, a citizen of the United States, and a resident of San Francisco, in the county of San Francisco and State of California, have invented certain new and useful Improvements in Torpedo Protection; and I do hereby declare the following to be a full, clear, and exact description of the invention, such as will enable others skilled in the art to which it appertains to make and use the same.

The present invention relates to ships and especially to a construction thereof adapted to prevent or greatly delay sinking as a result of accident or attack.

Protecting a ship against sinking by putting heavier steel construction in the hull and providing stronger decks, bulkheads and frames, has limitations which have been exceeded by modern explosives and the speeds obtained by modern ships. The kinetic energy of a rapidly moving ship or of a powerful explosion can not be resisted by mere rigidity of construction, within feasible limits, without the yielding of some parts of the construction. If the disturbing force is small in proportion to the strength of the resisting body, the latter yields only within the limits of its elastic strength and is comparatively unharmed, but no construction yet devised can withstand the destructive effect of modern explosives without considerable or even fatal damage. Not only adjacent the point of attack, but throughout the entire length of the ship, the effect of the explosive is apparent in a wrenching of the framework, disrupting of the bulkheads, and loosening or breaking of the rivets, so that as a matter of fact massiveness and rigidity of construction, by transferring the local distortion and displacements resulting from a collision or explosion extensively throughout the ship's structure, often become sources of danger while lightness of construction, whereby the energy of the explosion, slightly restrained, can therefore dissipate itself locally, may be an element of safety.

As an element of protection, in addition to heavier construction, various devices have been devised to absorb the energy of an explosion with the idea that this energy is thereby prevented from damaging the main

construction of the hull. Such devices as have been proposed, however, would at the present time have little or no effect in preventing destruction by the powerful weapons now in use.

To overcome the serious and fundamental structural limitations outlined above as well as the ineffectiveness of alleged protecting devices, the present invention briefly described contemplates the provision, within all of the watertight compartments of a vessel, of flexible supplementary walls or linings forming watertight baglike compartments to prevent the entrance of water in case the normal steel bulkhead walls of the compartments should be so strained and loosened as to fail to resist the incoming water. The present practice of dividing ships into many compartments is not only intended to reduce the chances of sinking in case of accident, but contributes largely to the necessary structural strength of the ship. It has therefore been assumed that in general compartments would be built as at present, and the flexible bulkheads used in connection with the steel bulkheads. However where more compartments, or different arrangements of compartments, are desired for flotation purposes than are necessary or desirable for strength alone, these flexible bulkheads could be used alone to divide larger steel walled compartments, and thus increase the subdivision of the ship to provide increased flotation in case of accident, without seriously increasing the weight or the cost of the ship's structure. The flexibility of the proposed walls permits them to yield without being injured by distortions and displacements which would loosen or tear the adjacent steel construction, while at the same time they are sufficiently reinforced to resist any pressure to which they may be subjected in case of emergency.

As tending to the attainment of the objects of the invention outlined above another feature thereof is the provision of certain closely attached deck plates above each compartment which, while held sufficiently to prevent shifting under normal usage, will be easily blown out by the pressure of gases in any compartment resulting from an explosion, thereby giving a vent for the gases upward, and thus reducing the destructive effect of the explosion upon the ship's bulkheads.

In order that my invention may be clearly understood and readily carried into effect I will describe the same with reference to the accompanying drawings showing one embodiment thereof.

Figure 1 is a longitudinal vertical section of the forward part of the hull of a ship showing the manner in which my invention is applied to the compartments and 10 doorways thereof;

Fig. 2 is a vertical transverse section through the hull of the ship.

Fig. 3 is an elevational view of a door associated with the construction of the invention; 15

Fig. 4 is a horizontal section through the door of Fig. 3;

Fig. 5 is a detail of the upper part of the door frame showing the mode of attachment 20 of the flexible compartment linings.

Fig. 6 is a sectional view showing the construction of the reinforced lining.

Fig. 7 is a face view of the same lining;

Fig. 8 is a detail view showing the mode 25 of attachment of the flexible linings; and

Fig. 9 is a section of the hull of a ship showing the action of the flexible linings after an explosion has taken place.

Referring now to the drawings, in which 30 similar reference characters denote similar parts throughout the several views, the hull is shown somewhat diagrammatically in Figs. 1 and 2, and may be of any suitable hull construction. It is provided with outer 35 plating 10 and three decks 11 each supported on deck beams. The interior of the hull between decks is divided into a number of compartments by transverse bulkheads 12. Communication between the compartments 40 is obtained through doorways closed by watertight doors 13 of any desired construction. The hull will be further subdivided by means of longitudinal bulkheads which, however, are omitted from the present drawing 45 since they are not necessary to a disclosure of the invention.

The construction described above shows in general the most essential elements of the hull and it is upon the rigidity and 50 reinforcing of these elements by appropriate braces, that the strength of the hull depends. It is usually sought to make the construction sufficiently strong so that compartments not directly subjected to accident or attack shall 55 remain intact and thereby tend to keep the ship afloat. As pointed out above, however, the destructive effects of a collision at high speed, or of a modern torpedo or mine, may be so great as to render even the strongest construction of little value for the above purpose.

In accordance with the present invention there is provided within each compartment a lining 14 composed of a network of wire 60 rope 15, Figs. 6 and 17, covered with water-

proof canvas or other fabric 16 attached to the network by fasteners 17 at the points of intersection of the strands. The wire rope and canvas lining is placed on the compartment wall with such a degree of looseness 70 that when the water or air pressure resulting from an injury to the ship comes upon it, it will belly out to a somewhat spherical shape, and the strength of the wire rope network is designed with reference to the 75 spherical arc thus formed and the maximum pressure that can come upon it so as to safely carry the resultant stresses. The size of the mesh of the wire rope network is similarly proportioned with respect to the 80 strength of the canvas or other watertight material. The lining is attached to the interior edges of each compartment by suitable fastening means 18 and at all corners as well as at the points 19 where the edges 85 of the lining are attached to the decks the joints should be made watertight. The edges of the linings should be attached to other linings nearest them in adjacent compartments, by fastenings 20 passing through 90 the steel compartment walls, so that they will be held approximately in position, even should the compartment structure be so damaged that its edges would be unable to support the flexible lining should a full head 95 of water come against it. The fastenings 20 may be made of loops of wire rope and the apertures where they pass through the plates may be packed with hemp or other material. Preferably the linings need not be 100 placed over the floors of the compartments as one layer will suffice for each compartment surface, and it would be more convenient to have them on the ceiling of the underneath compartments.

Each compartment lining will be provided with an auxiliary door on its side of the main door, as shown in Figs. 3, 4 and 5. An auxiliary door frame, comprising two members 21 and 22 between which the edges of 110 the lining 14 are firmly secured, is attached by a few bolts or other fastening devices 23 to the main door frame 24. The fastening devices 23 should be sufficient to retain the auxiliary frame in place under normal 115 conditions, but designed to give way if water pressure comes against the flexible bulkhead. Each auxiliary door frame is provided with a steel door 25 hinged thereto as at 26 and having latches 27.

In a ship provided with the construction described above certain deck plates over each of the compartments as at 28 should preferably be loosely fastened to their supporting beams so that they may be easily detached by an explosion. It is expected and intended that deck plates and flexible linings directly above the compartment in which an explosion occurs shall be torn loose or disrupted, as in this way the general de- 125 130

structive effects of the explosion in other directions, where the harm would be greater, will be reduced.

The destructive effects of an explosion and the action of the flexible linings in preventing the flow of water even though the plates and frames of the ship are torn away or wrenches are portrayed in Fig. 9.

It is not contemplated that the flexible compartment linings in the immediate vicinity of an explosion or other accident will not themselves be destroyed, for it is assumed they will not be able to withstand the terrific force of modern explosives. The decks, bulkheads and framework for a long distance from the point of the explosion might be wrenches and loosened, this being the reason for the loss of so many vessels which have been so designed that any two or sometimes more compartments can be flooded without causing the ship to sink. But the destruction of the corresponding flexible linings would be localized, since those portions not receiving the force of the explosion directly would yield readily, without rupture, to the distortion of much of the ship's structure by a modern mine or torpedo, which distortion, extending far beyond the local destructive effects of the explosion, destroys rigid steel bulkheads. Thus the flexible linings would form a series of bag-like compartments barring the progress of water throughout the greater portion of the hull of the ship. Furthermore, the loose deck-plates over the compartment or compartments where the actual explosion takes place would be blown out easily and quickly and so provide a number of outlets for the gases resulting from the explosion, which otherwise would tear their way in every direction with correspondingly greater destructive effect.

Various modifications or changes in the details of construction of my invention may be made without departing from the principle thereof.

I claim:

1. In a ship having a hull divided into a plurality of compartments, flexible linings or walls for the compartments, and means for supporting said linings upon the walls or edges of said compartments.

2. In a ship having a hull divided into a plurality of compartments, flexible linings or walls for the compartments, said linings being composed of canvas and wire mesh and means for attaching said linings to the surface or edges of said compartments and to each other.

3. In a ship having a hull divided into a plurality of compartments, a flexible lining or wall for each compartment composed of watertight material and a framework to which said material is attached, and means for supporting the linings upon the surfaces of the compartments.

4. In a ship having a hull divided into a plurality of compartments, a flexible lining or wall for each compartment composed of watertight fabric and a metallic network to which said fabric is attached, and means for supporting the linings from the edges or on the surfaces of the compartments.

5. In a ship provided with a plurality of compartments and communicating doorways therebetween, watertight flexible linings for the compartments, means for supporting the linings upon the walls or edges of the compartments, door frames inserted into the linings and surrounding the doorways between adjacent compartments, and doors mounted upon said door frames.

6. In a ship provided with a plurality of compartments and communicating doorways, watertight flexible linings for the compartments, means for supporting the linings upon the walls or from the edges of said compartments, and door frames registering with the doorways between the compartments and each comprising members to which the edges of the flexible linings are secured, and a door mounted upon each door frame.

7. In a ship provided with a plurality of compartments and communicating doorways, watertight flexible linings for the compartments, means for supporting the linings upon the walls or from the edges of said compartments, door frames registering with the doorways between the said compartments and comprising members to which the edges of the flexible linings are secured, a door mounted upon each door frame, and means for supporting said door frames upon the frames of said main doorways whereby they may be easily detached therefrom.

8. In a ship provided with a plurality of compartments, special deck-plates forming portions of the tops and bottoms of the compartments, supporting members for the deck-plates, means holding said deck-plates upon said supporting means but permitting the same to be easily detached therefrom, a watertight flexible lining for each compartment and means for attaching said linings to the walls or edges of the compartments.

In testimony whereof I affix my signature.
SAMUEL L. GRISWOLD KNOX.

It is hereby certified that in Letters Patent No. 1,243,427, granted October 16, 1917, upon the application of Samuel L. Griswold Knox, of San Francisco, California, for an improvement in "Torpedo Protection," errors appear in the printed specification requiring correction as follows: Page 1, line 37, for the word "explosive" read *explosion*; page 2, line 65, for the abbreviation and numerals "Figs. 6 and 17" read *Figs. 6 and 7*; and that the said Letters Patent should be read with these corrections therein that the same may conform to the record of the case in the Patent Office.

Signed and sealed this 29th day of January, A. D., 1918.

[SEAL.]

R. F. WHITEHEAD,

Acting Commissioner of Patents.
